UNITED STATES PATENT OFFICE

168,732

TOY AUTOMOBILE

Patrick J. Christopher, Geneva, N. Y.

Application September 20, 1951, Serial No. 16,692

Term of patent 7 years

(Cl. D34—15)

To all whom it may concern:

Be it known that I, Patrick J. Christopher, a citizen of the United States, residing at Geneva, State of New York, have invented a new, original, and ornamental Design for a Toy Automobile, of which the following is a specification, reference being had to the accompanying drawing, forming a part hereof.

Fig. 1 is a top plan view of a toy automobile, showing my new design;

Fig. 2 is a front elevational view thereof.

Fig. 3 is a side elevational view thereof.

The semi-spherical dome on the top of the toy is shaded to indicate transparency.

I claim:

The ornamental design for a toy automobile, as shown and described.

PATRICK J. CHRISTOPHER.
